MASONRY SAW

Edward A. Zuzelo, Narberth, Pa.

Application October 19, 1948, Serial No. 55,313

2 Claims. (Cl. 125-13)

1. *Chlorophytum comosum* (L.) Willd. (Asparagaceae)

1

My invention is an improved saw for cutting masonry and various other mineral and clay-type materials used in the construction of buildings.

Heretofore, saws of this general type have been deficient in that the breakage of the cutting blades has been excessive. My improvements prevent excessive operator pressure on the cutting blade and thereby eliminates the primary cause of the undue stresses and strains which shorten the cutting blade life.

The principal objects of my invention are to provide a masonry saw having a constant, pre-determined pressure on the cutting blade throughout the length of the cut; to provide means for securing the cutting blade in any desired cutting position; to provide means for varying the height of the platform above the base carriage without lifting the platform from its supports; and to provide means for adjusting the pressure on the cutting blade.

Fig. 1 is a perspective elevational view of my masonry saw embodying my improvements; Fig. 2 is a side elevational view of the masonry saw partly cut away and partly in cross-section; Fig. 3 is a top plane view taken at the level of the platform and partly cut away; Fig. 4 is an enlarged top plane view taken on the line 4—4 of Fig. 2 showing in detail the operation of the locking device; Fig. 5 is an enlarged perspective view of a section of the foot lever extension and platform bar; Fig. 6 is an enlarged side elevational view of one of the platform supporting linkages.

As illustrated in the drawings, my preferred form of masonry saw comprises a cutting blade 1 journaled on a shaft mounted on a platform 2 which carries the motor 3 for driving the blade 1 by means of endless belts 4 secured to the shafts of the motor 3 and cutting blade 1.

The platform 2 pivots about a transverse bar 5 whose ends are seated in recesses 6 cut in the end of the upper link member 1 which can support the platform 2 either directly from the bottom of the right angle channel-piece 24 forming part of the carriage base 8, or it may support the platform 2 indirectly by depending on the pin 9 and the lower link 10 which is mounted on a rod 11 and rotates therewith. The rod 11 has its ends journalled in the standard 12 projecting up from the carriage base 8.

The movement of the platform 2, which is unbalanced in favor of the cutting blade end of the platform, is controlled by the operator with the use of a foot lever 13 having an extension bar 14 connected therewith and which is mounted on a

5 pivot member 15 having its ends journalled in the rear legs of the carriage base 8. A depending arm 16 is secured to the platform 2, immediately behind the pivot bar 5, and projects downwardly to and through the opening 19 cut in the extension member 20 which is attached to the bar 14. The arm 16 has a series of holes 17 cut in the lower portion of the arm 16 for the insertion of a pin 18 which should be of sufficient length to project beyond the limits of the opening 19. As can be seen in Fig. 5, the depending arm 16 is not secured to the extension member 20 but merely projects through the opening 19 and is free to move downwardly through the opening. Its 10 upward movement, however, is checked by the stud 18 meeting the bottom surface of the extension member 20. Thus, when the operator depresses the foot lever 13, thereby elevating the extension member 20, the depending arm 16 is 15 not drawn upward by force of the foot lever but follows the movement of the extension arm 20 only because of the force of gravity acting on the unbalanced platform, causing it to drop until the depending arm 16 has been drawn up to a 20 point where the pin 18 meets the under surface of the extension member 20. As gravity is the only force acting on the cutting blade it follows that for a given position of unbalance the pressure at the cutting edge is constant at all times 25 and is not subject to variations in the operator's foot pressure. Thus, an even cut is assured. Springs 21 suspended from the channel 22 forming 30 a part of the base 8 are attached to the foot lever 13 and are of sufficient strength to keep the foot lever 13 and cutting blade 1 in raised position 35 when the foot lever 13 is released by the operator.

The height of the platform 2 may be varied to accommodate the variations in the size of the articles to be cut by rotation of the hand lever 40 23, which is an elongation of the supporting rod 11. As shown in Fig. 6, when the handle 23 is in an upright position the link 10 mounted on the rod 11 leans against the rear channel of the standards 12. When, however, the handle 23 is 45 turned downwardly the rod 11 and, therefore, the link 10, which is frozen to the rod 11, rotates until the lower end of the link 10 carrying the pin 9 rests on the channel 24. The link member 1 and the rod 5 held by the link member 1 is thus shifted 50 from the position shown in solid outline in Fig. 6 to the position shown in phantom outline. A member 12a affixed to the standard 12 guides the pivot rod 5 in its movement from one position to the other. A locking screw 39 may be used to 55

secure the links in given position against accidental turning of the handle 23.

The masonry or tile to be cut is placed on a carriage 25 mounted on wheels 26 which ride on the upturned edges of the channel 24 and can be moved therewith along to the cutting position desired. The carriage 25 carries therewith an end member 27 against which the masonry may be held for the positioning of the masonry in relation to the cutting blade 1. After the masonry has been placed on the carriage 26 in suitable position, the foot lever 13 is depressed by the operator thereby raising the extension member 20 upward along the bar 16. As the bar 16 is not fastened to the extension member it does not necessarily move at the same rate of speed nor due to the effect of inertia at the same instant as the extension member 20 but varies its rate of movement in proportion to the unbalance of the platform 2 about its pivot 5. The movement of the cutting blade 1 and the platform 2 about the pivot 5 causes the cutting blade 1 to come into contact with the masonry on the carriage 25 and the unbalance of the platform about its pivot will produce a steady pressure to be applied to the cutting blade edge. As the unbalance is constant the pressure is necessarily constant and the cutting blade 1 is thereby relieved of any undue strains or stresses that tend to shorten the life of the cutting blade.

The foot lever 13 may be dispensed with whenever the cutting blade may be secured in one position for cutting. To secure the cutting blade in a given position, the locking lever 28 is rotated clockwise about its pivot member. The rollers 29 and 30 mounted on the lever 28 thereby force the bar 31 to move counterclockwise about its pivot 32 bringing the free end of the bar 31 into bearing contact with the depending arm 16 which on its other side bears against the platform lever 33 which in turn bears against the end of the stud 36 mounted in the bracket 35. The upper end of the platform lever 33 is fastened to the end of the platform 2 adjacent the motor while the lower end is guided by the post 34 projecting from the bracket 35. The locking lever 28 can securely hold the platform 2 in any desired position by the bearing friction between the members 31, 16, 33 and the end of the stud 36 even against the tension of the spring 21. The bar 31 is securely held against jarring or vibration by the rollers 29 and 30.

The top of the cover 37 fitting over the belts 4 provides a slideway on which the weight 38 may be secured in various positions so as to vary the position of the center of gravity of the platform 2 thereby changing the pressure on the cutting blade. As the weight 38 is moved toward the cutting blade end of the platform the transverse axis will move away from the pivot bar 5 toward the cutting blade 1 and the pressure on the cutting blade will vary proportionately. The position for maximum pressure on the cutting blade is that shown in Fig. 1.

The saw may also be provided with a hose 40 having jets at the end thereof mounted on the inside of the cover shielding the cutting blade 1 which eject streams of water to both sides of the cutting blade for wet or "dustless" cutting.

Having described my invention, I claim:

1. A masonry saw comprising a base having standards, a platform mounted on a rod, a cutting blade and motor for operating said cutting blade mounted on opposite ends of said platform, said rod being positioned on the motor side of the transverse axis of said platform and having its ends recessed in links supported by said standards, means for altering the position of said links to vary the height of said platform and means for shifting the position of said transverse axis.
2. A masonry saw comprising a base, a platform mounted on pivot means above said base, a cutting blade mounted on one end of said platform, a motor mounted on the opposite end of said platform, said cutting blade movable to and from said base, an arm secured to said platform between its transverse ends and projecting toward said base, a second arm depending from an end of said platform and projecting toward said base and the free end of said first named arm and means to secure both of said arms against movement.

EDWARD A. ZUZELO.
